STRIKING CASTING

Donald S. Barrows, Rochester, N. Y., assignor to
The Symington Company, New York, N. Y., a
corporation of Maryland

Application January 10, 1928, Serial No. 245,743
Renewed September 21, 1933

18 Claims. (Cl. 213—60)

This invention relates to combined striking castings for railway cars and more particularly to such adapted to receive replaceable wear blocks.

The principal object of my invention, generally considered, is to provide a combined casting formed with portions serving, respectively, as a coupler stop or striking casting and a sill tie member or coupler carrier iron and provided with means for connecting said casting to the associated sills and cover plate of a car, removable wear blocks being provided above and below the stem of an associated coupler whereby upon removal thereof a coupler of the swivel butt type or one with a relatively large butt may be readily applied or removed.

An object of my invention is to provide a combined striking casting and coupler carrier member suitable for use with a swivel butt coupler and adapted to receive top and bottom wear blocks simultaneously retained by common fastenings and so formed that upon removal thereof the butt of a swivel butt coupler may be readily applied or removed.

Another object of my invention is to provide a combined striking casting and sill tie member adapted for receiving striking and carrier blocks respectively disposed above and below the stem of an associated coupler, said blocks being adjustable up and down to correct the coupler height and keep the top clearance at a practical minimum.

A further object of my invention is to provide a combined striking casting for use with railway cars adapted to receive striking and coupler carrier wear blocks which blocks are interchangeable, reversible and renewable upon wear or breakage.

A still further object of my invention is to provide a combined casting adapted for connection with the center sills of a car and provided with a sill tie portion adapted to support a coupler carrier block and a striking portion formed with pockets adapted to receive a similar striking wear block, those portions of the casting receiving said blocks being large enough to permit limited vertical movement of said blocks, adjusting washers or liners being provided between said blocks and the casting for positioning the same at the desired elevations, common retaining pins being also provided for holding said blocks in place and cotters 50 extending through bosses on said combined casting above said pins for locking the same in place.

Other objects and advantages of the invention relating to the particular arrangement and construction of the various parts will become apparent as the description proceeds.

Referring to the drawings illustrating my invention, the scope whereof is defined by the appended claims.—

Figure 1 is a plan view, partly in horizontal section illustrating an embodiment of my combined casting with an associated coupler, yoke, connecting key and center sills.

Figure 2 is a longitudinal vertical sectional view of the construction shown in Figure 1.

Figure 3 is a front elevational view, partly in vertical section, of the combined casting, the associated coupler being removed.

Figure 4 is a side elevational view of said casting connected to associated sills.

Figure 5 is a fragmentary horizontal sectional view on a line corresponding to the line 5—5 of Figure 4 but showing a modification.

Referring to the drawings in detail, like parts being designated by like reference characters, there is shown a combined casting 1 formed with a 20 coupler striking or stop portion 2, a coupler carrier iron or sill tie portion 3 and vertical side or connecting portions 4. Said side portions are formed with rearwardly extending ear or web portions 5, preferably lying on the outside of and adjacent to the web portions 6 of the center or draft sills 7 and connected thereto by a plurality of rivets 8. Said web portions are also preferably bifurcated or formed as upper and lower sections 9 and 10, respectively, leaving notches 30 11 therebetween, said notches partially embracing the slots 12 provided in the associated center sills 7 for the reception of the usual form of draft key 13. For strengthening the webs of the sills around the slots 12 rearwardly of the sections 9 and 10, partial cheek plates of the usual form (not shown) may be provided to supplement said sections which form, in effect, the forward portions of cheek plates.

The striking portion 2 is preferably formed with a rearwardly extending web or flange 14, preferably downwardly offset with respect to the striking portion so that the top thereof lies on a level with the tops of the sills 7 and is adapted for connection with the sill cover plate (not shown), said web being apertured for rivets as indicated at 15. Said web or shelf portion 14 is preferably strengthened by a depending web or flange 16 and rearwardly extending tapering webs 16' which gradually decrease in depth and merge into the web 14.

The upper ends of the side portions 4 are formed with pockets 17 defined by the uppermost web of the striking portion 2, the vertical webs 18 of the side portions 4 which at the pockets 17

are preferably outwardly offset as illustrated, horizontal flanges 19 extending inwardly from said webs 18 and the depending flange or web portions 16, previously described. Disposed in 5 said pockets 17 is a striking wear block 20, the ends of which rest and are supported on the flanges 19 and the front web of which normally extends slightly forward of the front edge of the striking portion 2, whereby upon buff the associated coupler 21 normally engages the wear block 20 and relieves the striking portion 2 of wear. The pockets 17 are somewhat larger in vertical dimension than the wear block 20 whereby 10 vertical adjustment of said block is permitted, 15 said adjustment being desirably effected by positioning shims or washers 22 above or below said block as desired. Said wear block 20 is desirably formed box-shape in section or as a hollow beam substantially rectangular in cross-section.

20 A similar construction is provided above the sill tie portion 3, the lower ends of the sides 4 being for that purpose provided with pockets 23 preferably of the same size as the pockets 17 and defined by similarly offset portions of the webs 25 18 and overlying flanges 24 from said webs and the upper web 25 of the sill tie portion 3, the ends of which are preferably upwardly offset as illustrated. A lower or carrier block 26 is received in the pockets 23 and rests on the upwardly offset portions of the web 25 and for convenience the block 26 is preferably constructed of the identical size and shape as the block 20 and both of said blocks are preferably retained in position by common fastening or connecting means. As in connection with the block 20 the pockets 23 are preferably formed larger than the ends of the block 26 and washers 27 are provided for adjusting the height of the carrier block 26. Said connecting means preferably takes the form of vertical pins or rods 28 received in pockets 29 in the sill tie portion 3 or upper web 25 thereof and registering apertures, 30 in the carrier block, 31 in the washers or liners 27, 32 in the flanges 24, 33 in the flanges 19, 34 in the wear block 20, 35 in the washers or liners 22 and 36 in the top of the combined casting or striking portion 2 thereof.

For securely locking the rods or pins 28 in place the striking portion 2 of the casting is preferably formed with upstanding collars or bosses around 50 the apertures 36 which are provided with horizontal apertures therethrough for receiving cotter pins or other retaining devices 37 whereby undesired removal or loss of the pins 28 is prevented.

Referring now to the modification of my invention shown in Figure 5, a construction is there disclosed which permits swinging the removable members or wear block upon withdrawing only one pin, whereby the coupler may be inserted or removed when the wear blocks are 55 60 swung outwardly, as indicated in dot-dash lines, while the same are still connected to the striking casting at one end.

In order to permit such swinging, both ends of both wear blocks, the lower one 26^a only being 65 shown as illustrative, are preferably provided with ends rounded as indicated at 39, so that one or both blocks can be swung outwardly like gates about either end upon removal of the other pin 28^a only, to provide an enlarged aperture 40^a above the sill tie portion 3^a for the same purpose as in the first embodiment. Except as specifically disclosed in connection with the present embodiment the same may correspond substantially with that of the first embodiment.

70 From the foregoing description, taken in con-

nection with the accompanying drawings, it will be seen that I have devised a combined striking casting and sill tie member which is formed with pockets in the upper and lower portions thereof adapted to respectively receive top and bottom wear blocks which are simultaneously retained by the same or common fastenings. Said wear blocks are formed adjustable up and down to correct the coupler height and keep the top clearance at a practical minimum.

For convenience and economy of manufacture the blocks are desirably formed interchangeable, reversible and renewable for wear or breakage. The adjusting means for said blocks preferably takes the form of washers which are held in place by the pins which retain the blocks in position. The striking casting is so formed that upon removal of the blocks an aperture 40 of ample size is provided for the insertion and withdrawal of the coupler 21 and particularly the 20 swivel butt portion 38 thereof which, as will be understood, is of greater size than the butt of a coupler with a rigid stem. By providing removable blocks above and below the stem of the coupler not only is it possible to insert or remove 25 the butt of the coupler while assembled, especially as the flange or web 16 is decreased in depth above said coupler and the web 25 slightly offset downwardly directly beneath said coupler, but the height of the coupler may be accurately adjusted by positioning the lower block 26 and the clearance above said coupler maintained at a practical minimum by adjusting the position of the upper block 20. Although the front webs of the blocks 20 and 26 are preferably made thicker 30 or heavier than the rear webs, as illustrated, to allow for wear on said front faces, I do not wish to be limited to this construction as it will be understood that said blocks are reversible.

On account of providing removable blocks 20 40 and 26 above and below the stem of the associated coupler 21, rather than having merely one block of correspondingly increased size which is adapted for removal when the butt of the coupler is inserted or withdrawn, I am enabled to decrease the 45 overall height of the combined casting, as will be understood, and at the same time provide a casting which is more desirable in other respects in that the principal wearing portions thereof are renewable, and, if desired, swingable to inoperative position without complete detachment from the striking casting.

Having now described my invention, I claim:

1. A combined casting comprising portions serving, respectively, as a striking casting and sill tie member, said casting being formed with pockets adjacent the upper and lower portions thereof, defined by normally horizontal and vertical web portions, and top and bottom wear blocks, respectively received in said pockets and simultaneously retained by common fastenings intersecting all of said horizontal web portions, said blocks being spaced to receive the stem of an associated coupler therebetween.

2. A combined casting comprising portions serving, respectively, as a striking casting and sill tie member, wear blocks receivable in pockets respectively disposed adjacent the top and bottom of said casting, said top block serving as a coupler stop member or striking wear block and the bottom block serving as a coupler carrier block, said blocks being interchangeable.

3. A combined casting comprising portions serving, respectively, as a striking casting and sill tie member, wear blocks respectively held in

place adjacent the striking portions and above the sill tie member and spaced to receive the stem of an associated coupler therebetween, the end portions of said blocks and adjacent normally horizontal web portions of the casting being formed with registering apertures, two retaining pins, one insertable through all of said apertures on one side and the other through all those on the other, and resting on shouldered portions of the casting, and locking means disposed above said pins for preventing undesired removal thereof.

4. A combined casting comprising portions serving, respectively, as a striking casting and sill tie member, and a wear block held in place adjacent the striking portion, said block being spaced above the sill tie member for receiving the stem of a coupler therebeneath and held in place by normally vertical pins through its end portions, said end portions being formed with end surfaces curved coaxially of the pins so that the block is swingable to inoperative position about either end pin when the other pin only is removed.

5. A combined casting comprising portions serving, respectively, as a striking casting and sill tie member, and a wear block removably held in place above the sill tie member, said block being spaced to permit receiving the stem of a coupler between the same and the striking portion, said block being held in place by normally vertical pins through the end portions thereof, said end portions being formed with end surfaces curved coaxially of the pins so that the block is swingable to inoperative position about one end pin upon removal of only the pin through the other end.

6. A combined casting comprising portions serving, respectively, as a striking casting and sill tie member, wear blocks respectively held in place adjacent the striking portion and above the sill tie member, with their end portions disposed close to confining web portions of said casting and spaced from one another to receive the stem of an associated coupler therebetween, the end portion of each block and the adjacent portions of the casting being formed with apertures registering with corresponding apertures in the end portions of the other block, a retaining pin insertable through each set of registering apertures, the ends of said blocks being curved to permit swinging of one or both to inoperative positions about one of said pins when the other only is removed.

7. A combined casting comprising portions serving respectively as a striking casting and sill tie member, wear blocks with portions received in pockets defined by upper, lower and side walls forming parts of said combined casting and respectively held in place adjacent the striking portion and sill tie portion, said blocks being spaced to accommodate the stem of an associated coupler therebetween, and common fastening means intersecting said upper and lower walls and retaining both blocks in place.

8. A combined casting comprising portions serving, respectively, as a striking casting and sill tie member, the striking casting portion comprising a top web, side webs, flanges underlying the end portions of said top web and defining forwardly opening pockets adjacent said side webs, a wear block disposed adjacent the striking portion, with its ends received in said pockets, and spaced above the sill tie portion to receive the stem of an associated coupler therebetween, the ends of said block and the adjacent portions of said top web and flanges being formed with regis-

tering apertures, and upright pins disposed in said apertures for holding said block in place.

9. A combined casting with a coupler stem receiving opening and comprising portions serving, respectively, as a striking casting and sill tie member, the upper portion of said casting being pocketed and a striking wear block inserted longitudinally of said casting with its ends received in said pocketed portions and restricting the opening, said pocketed portion permitting limited vertical movement of the wear block therein, adjusting means vertically disposed between said block and parts of the walls of the pocketed portion for properly positioning said block to maintain the clearance above an associated coupler stem at a practical minimum, and means serving to simultaneously retain said block and adjusting means.

10. A combined casting comprising portions including an upper web with a flange depending therefrom and serving, respectively, as a striking casting and sill tie member, a block normally engaging said flange, disposed adjacent the striking portion and spaced from the sill tie member to receive the stem of an associated coupler therebetween, the ends of said block being received in pockets formed in the sides of said casting above said sill tie member and defined by said web and shelf portions disposed therebeneath, upright pins disposed in registering apertures in said upper web and shelf portions and serving to retain said block in place, and means for preventing undesired removal of said pins.

11. A combined casting comprising portions serving, respectively, as a striking casting and sill tie member, said portions being spaced a relatively great distance for receiving an enlarged butt of a coupler therebetween, said casting comprising an upper web, shelf portions disposed therebeneath, and a depending transverse flange defining forwardly opening pockets, a wear block normally abutting said flange, with its ends received in said pockets for restricting the coupler stem receiving opening and reducing the clearance above such a stem to a practical minimum, and upright pins intersecting said upper web, said shelf portions and the portions of said wear block therebetween for holding the latter in place.

12. A combined casting comprising portions serving, respectively, as a striking casting and sill tie member, and formed with pockets defined by upper and lower walls and side wall portions of the casting, wear blocks held in place adjacent the striking portion and above the sill tie member, respectively, and with end portions disposed in said pockets, fastening means for said blocks intersecting said upper and lower walls, and washers encircling said fastening means for vertically adjusting the positions of said blocks with respect to said casting, said blocks being spaced to receive the stem of an associated coupler therebetween.

13. A combined casting comprising portions serving, respectively, as a striking casting and sill tie member, said portions being spaced to permit the insertion of the butt of a swivel butt coupler therebetween, those portions of the casting connecting the striking and sill tie portions being formed with forwardly opening pockets defined by upper, lower and side web portions, wear blocks with end portions received in said pockets and spaced to receive the stem of a coupler therebetween, means to secure said end portions to said casting, and means to adjust said blocks up

and down to correct the coupler height and keep the top clearance at a practical minimum.

14. A combined casting comprising portions serving, respectively, as a striking casting and sill tie member, the upper portion of said casting being formed with pockets each defined by upper, lower and side web portions and receiving a striking wear block when inserted longitudinally of the casting and the lower portion being formed with pockets each defined by upper, lower and side web portions and receiving a coupler carrier wear block when inserted longitudinally of the casting said pockets permitting limited movement of the wear blocks therein, means for securing each end of each block in a pocket, and adjusting washers or liners disposed between said wear blocks and at least some of said web portions for properly positioning said blocks for correcting the height of an associated coupler and maintaining the clearance above said coupler at a practical minimum.

15. A combined casting comprising portions serving, respectively, as a striking casting and sill tie member, the sill tie member comprising a top web extending between side webs of said casting, flanges extending from said side webs and, with said top web and side webs, defining pockets, a wear block with end portions received in said pockets and spaced from the striking portion to receive the stem of an associated coupler therebetween, the ends of said block and adjacent top web and flanges of the casting being formed with registering apertures, upright pins disposed in said apertures, the sill tie member having shouldered portions below said apertures to engage the lower ends of said pins and limit downward movement thereof, and means for preventing undesired removal of said pins.

16. A combined casting comprising portions serving, respectively, as a striking portion and sill tie member, the sill tie member comprising a

top web, side webs, flanges overlying the end portions of said top web and defining forwardly opening pockets adjacent said side webs, a wear block disposed adjacent said sill tie member with its ends received in said pockets and spaced below the striking portion to receive the stem of an associated coupler therebetween, the ends of said block and the adjacent portions of said top web and flanges being formed with registering apertures, and upright pins disposed in said apertures for holding said block in place.

17. A combined casting comprising portions serving, respectively, as a striking casting and sill tie member, said portions being connected by sides provided with rearward continuations adapted for connection with associated car sills, said sides being provided with pockets respectively disposed adjacent the upper and lower ends thereof and each defined by normally horizontal upper and lower web portions and the side portions of the casting therebetween, a striking wear block with end portions received in said upper pockets, and a coupler carrier wear block with end portions received in said lower pockets, said blocks being reversible for increasing the life thereof.

18. A combined casting comprising portions serving, respectively, as a striking casting and sill tie member, said casting being formed with pockets, each defined by an upper and a lower web portion, and a side web of said casting, and wear blocks with their end portions received in said pockets and respectively located adjacent the striking portion and sill tie portion, said blocks being spaced to accommodate the stem of an associated coupler therebetween, and means to secure the blocks in said pockets, said pockets and said means being so formed and associated as to permit removal of said blocks when the coupler stem is in position between said blocks.

DONALD S. BARROWS.
